(57) **CLAIM**

We claim the ornamental design for an end cap, as shown and described.

DESCRIPTION

FIG. 1 is a front perspective view of an end cap showing our new design;

FIG. 2 is a front view of the end cap as shown in FIG. 1;
FIG. 3 is a rear view of the end cap as shown in FIG. 1;
FIG. 4 is a right side view of the end cap as shown in FIG. 1;
FIG. 5 is a left side view of the end cap as shown in FIG. 1;
FIG. 6 is a top view of the end cap as shown in FIG. 1; and,
FIG. 7 is a bottom view of the end cap as shown in FIG. 1.
The broken lines shown represent unclaimed subject matter only and form no part of the claim.
